UNITED STATES PATENT OFFICE

136,208

DESIGN FOR A V-SHAPED TREAD MEMBER FOR SHOES

Henry Ghez and Oscar Ghez, New York, N. Y.

Application May 6, 1942, Serial No. 106,804

Term of patent 7 years

To all whom it may concern:

Be it known that we, Henry Ghez and Oscar Ghez, both citizens of Tunisia, Africa, of 30 Rockefeller Plaza, New York, N. Y., U. S. A., have invented a new, original, and ornamental Design for a V-Shaped Tread Member for Shoes, of which the following is a specification, reference being had to the accompanying drawing, forming part thereof.

Fig. 1 is a front elevational view of a V-shaped tread member for shoes, showing our new design;

Fig. 2 is a side elevational view of the same as seen from the right in the direction of the arrow 2 on Fig. 1;

Fig. 3 is a longitudinal sectional view on line 3—3 of Fig. 1; and

Fig. 4 is a transverse sectional view on line 4—4 of Fig. 1.

The design is particularly characterized by the fact that in a V-shaped member the section across any portion thereof which is free of the upward projections shows a rounded form of beveling at the edges, while at the lower junction is a projection in the form of a truncated cone and spaced from the same along the center of each of the two arms of the V are two similar projections, and finally upon the upper end of each arm along the center thereof is an elongated projection with rounded ends and bevelled edges, all of the projections being of substantially the same height. The elongated projection upon each arm is in line with the two truncated conical projections on the same arm and also the first mentioned projection while itself being spaced a slight distance within the end of the arm and said end in each case being rounded concentrically with the rounded end of the elongated projection respectively located on the arm.

We claim:

The ornamental design for a V-shaped tread member for shoes, substantially as shown and described.

OSCAR GHEZ.
HENRY GHEZ.
